Primary Examiner — Robin V Webster(74) *Attorney, Agent, or Firm* — Aleksander Medved(57) **CLAIM**

The ornamental design for a spray gun cup receptacle, as shown and described.

DESCRIPTION

FIG. 1 is a perspective view of a spray gun cup receptacle embodying the new design;

FIG. 2 is a front view of a spray gun cup receptacle embodying the new design;

FIG. 3 is a rear view of a spray gun cup receptacle embodying the new design;

FIG. 4 is a left side view of a spray gun cup receptacle embodying the new design;

FIG. 5 is a right side view of a spray gun cup receptacle embodying the new design;

FIG. 6 is a bottom view of a spray gun cup receptacle embodying the new design; and,

FIG. 7 is a top view of a spray gun cup receptacle embodying the new design.

The broken line showing of portions of the spray gun is included for the purpose of illustrating and forms no part of the claimed design.

1 Claim, 4 Drawing Sheets(56)
